(57) **CLAIM**

The ornamental design for a switch assembly with escutcheon, as shown and described.

DESCRIPTION

FIG. 1 is a perspective view of a switch assembly with escutcheon in a first position in accordance with the subject disclosure.

FIG. 2 is top plan thereof;

FIG. 3 is a bottom plan view thereof;

FIG. 4 is a left side view thereof;

FIG. 5 is a right side view thereof;

FIG. 6 is a rear elevation view thereof;

FIG. 7 is a front elevation view thereof;

FIG. 8 is a perspective view of the switch assembly with escutcheon in a second position thereof;

FIG. 9 is top plan view thereof;

FIG. 10 is a bottom plan view thereof;

FIG. 11 is a left side view thereof;

FIG. 12 is a right side view thereof;

FIG. 13 is a rear elevation view thereof; and,

FIG. 14 is a front elevation view thereof.

The broken line showings of the switch assembly with escutcheon are included for the purpose of illustrating the environment, and portions of the switch assembly with escutcheon and form no part of the claimed design.

1 Claim, 14 Drawing Sheets
